UNITED STATES PATENT OFFICE.

WILLIAM KOCH, OF NEW YORK, N. Y.

DESIGN FOR A QUILTING OR EMBROIDERY PATTERN.

SPECIFICATION forming part of Design No. 16,725, dated June 8, 1886.

Application filed January 18, 1886. Serial No. 189,005. Term of patent 14 years.

To all whom it may concern:

Be it known that I, WILLIAM KOCH, a citizen of the United States, residing in the city, county, and State of New York, have invented and produced a new and original Design for Quilting or Embroidery Pattern, of which the following is a specification, reference being had to the accompanying drawings, and to the letters of reference marked thereon, making a part thereof, in which—

Figure 1 illustrates one of the principal features of my design; Fig. 2, a systematic repetition thereof in the design, and Fig. 3 the complete design.

The principal feature of my design is the character **A**, consisting of an ogee whose two semicircular curves, *b b'*, are of equal radii, terminating at one end in a straight line, *c*, equal in length to one-half the distance between the extremities of the ogee, and which extends in a direction coincident with the centers of the arcs described by its inner and outer curves.

In the complete design a series of the characters **A A** appear in double rows, (see Fig. 3,) with the straight lines *c c* thereof in each row coinciding in direction and each bisecting the ogee *b b'* next preceding it. The straight lines in the several rows are parallel, and the opposite curves *b b* upon one side in each row are in contact centrally with the middle of the opposite curve *b' b'* in the adjacent row, the

relative position of the parallel straight lines in the several rows being such as that an imaginary line, *x x*, drawn to unite the ends of the counterpart straight lines in two or more of the rows (see Fig. 3) shall form a right angle therewith.

I claim as my invention—

1. The design for quilting or embroidery pattern herein shown and described, the same consisting of the double rows of ogees *b b'* and the straight lines *c c*, each bisecting the first ogee and joining the end of the second ogee next preceding it.

2. The design for quilting or embroidery pattern herein shown and described, the same consisting of the double rows of ogees *b b'* and the straight lines *c c*, each bisecting the first ogee and joining the end of the second ogee next preceding it, the opposite curves in the adjacent rows being in contact, and the several parallel straight lines in a relative position admitting of an intersection of their ends by an imaginary line, *x x*, drawn at right angles therewith.

In testimony whereof I have signed my name to this specification in the presence of two subscribing witnesses.

WILLIAM KOCH.
